(57) CLAIM

The ornamental design for a border fence section, as shown and described.

DESCRIPTION

FIG. 1 is a front perspective view of the border fence section showing our design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The dash-dash broken lines in the figures depict portions of the article and form no part of the claimed design. The dot-dash broken lines represent boundaries of the claimed design and form no part thereof.

1 Claim, 5 Drawing Sheets

FIG. 3

FIG. 4

FIG. 5

FIG. 6
